(57) **CLAIM**

The ornamental design for a tie standoff, as shown and described.

DESCRIPTION

FIG. 1 is a top perspective view of a tie standoff, shown in use with a tie.

FIG. 2 is a top perspective view of the tie standoff of FIG. 1, shown alone.

FIG. 3 is a bottom perspective view of the tie standoff of FIG. 2.

FIG. 4 is a top view of the tie standoff of FIG. 2.

FIG. 5 is a front view of the tie standoff of FIG. 2.

FIG. 6 is a rear view of the tie standoff of FIG. 2.

FIG. 7 is a bottom view of the tie standoff of FIG. 2.

FIG. 8 is a first side view of the tie standoff of FIG. 2; and,

FIG. 9 is an opposite side view of the tie standoff of FIG. 2.

The broken lines in the drawings depict portions of the tie standoff that form no part of the claimed design. The additional broken lines in FIG. 1 depict environmental subject matter that forms no part of the claimed design. The dot-dash broken lines denote the boundaries of the claim and form no part thereof.
